Primary Examiner — Kendra Leslie Hamilton(74) *Attorney, Agent, or Firm* — Nelson Mullins Riley & Scarborough LLP(57) **CLAIM**

The ornamental design for an oral-motor therapy pendant, as shown and described.

DESCRIPTION

FIG. 1 is a top, front, left perspective view of an oral-motor therapy pendant, showing my design in a condition for use; FIG. 2 is a left side elevation view of the oral-motor therapy pendant of FIG. 1;

FIG. 3 is a right side elevation view thereof;

FIG. 4 is a top plan view thereof;

FIG. 5 is a bottom plan view thereof;

FIG. 6 is a front elevation view thereof; and,

FIG. 7 is a rear elevation view thereof.

The portions shown in broken lines form no part of the claimed design.

1 Claim, 4 Drawing Sheets(56)
